LOUIS SNYDER, OF HARTFORD, CONNECTICUT.

PADLOCK.

1,209,894.

Specification of Letters Patent. Patented Dec. 26, 1916.

Application filed October 25, 1916. Serial No. 127,568.

To all whom it may concern:

Be it known that I, LOUIS SNYDER, a citizen of the United States, residing at Hartford, in the county of Hartford and State of Connecticut, have invented a new and useful Improvement in Padlocks, of which the following is a specification.

This invention relates to the types of padlocks which are so constructed that they will unlock and the hasps will spring open when keys of the proper shape are merely thrust into the keyhole.

The object of the invention is to produce a simple and cheap padlock of this class which is so constructed that it is very strong and so protected that it is very secure. In attaining this end, the tumbler which engages the hasp and locks it closed, the guard which protects the locking tumbler and which must be lifted by a properly shaped key before the tumbler can be reached and moved for unlocking the hasp, and the shield which co-operates with the guard in protecting the tumbler against being operated by anything but the proper key, are arranged in operative position on a back plate, and then the casing is cast about them so as to be in a single piece with no openings but the two for the ends of the hasp and the keyhole.

In the views which illustrate an embodiment of the invention Figure 1 shows a section of a padlock with the hasp locked in closed position. Fig. 2 is a similar view with a key inserted and the hasp unlocked and thrown open. Fig. 3 shows an edge view of the padlock. Fig. 4 is a section on the plane indicated by the line 4-4 on Fig. 1.

40 The casing 1 is cast to the desired shape in a single piece of any suitable metal. One end of the hasp 2 is secured in an opening in the end of the casing by a pivot pin 3 in such manner that the other end of the hasp 45 may be swung into and out of the other opening in the end of the casing. A spring 4 coiled about the pivot pin and having one end engaging the wall or casing and the other end engaging the hasp tends to throw 50 the hasp open. The end of the hasp inside of the pivot is shaped to provide a locking shoulder 5.

In one side of the casing and conforming approximately to the outline of the side wall 55 is a plate 6. The locking tumbler 7 is pivoted to this plate by a stud 8. A spring 9

draws the tumbler so that its upper end 10, when the hasp is closed, engages the locking shoulder 5 and prevents the hasp from turning open. The guard 11, which is formed 60 of a strip of spring metal, has one end secured to a block 12 that is fastened to the back plate. The other end of the guard is bent inward so as to press tightly against the back plate and form a barrier 13 between the keyhole 14 and the lower end 15 of the locking tumbler. This barrier must be moved outward transversely with relation to the plane of the locking tumbler before the lower end of the locking tumbler 70 can be engaged by anything for swinging it so as to unlock the hasp. On the outer side of this barrier at the end of the guard and projecting toward the keyhole is a thin wedge-shaped wing 16. The location of this 75 wing may be varied as desired according to the shape of the key to be used. Extending from the side wall of the casing adjacent to the upper edge of the keyhole to the upper edge of the guard is a shield 17. This shield 80 prevents the thrusting of a wire or other piece of metal past the guard and into engagement with the lower end of the tumbler for unlocking it.

When a key 18 of the proper shape is 85 thrust through the keyhole, it first engages the wing 16 and lifts the barrier 13 on the end of the guard out of the way, and then it engages the lower end 15 of the tumbler and turns it so that the hasp is released and its 90 spring allowed to throw it open. The key must be of such shape that it can be inserted into the key hole; it must be of such shape that it will engage the wing and lift the barrier on the end of the guard; and it also 95 must be of such shape and thickness that after the barrier has been lifted out of the way it will engage the lower end of the locking tumbler which is spaced a little distance in front of the back plate so that if the 100 guard should be lifted by a thin piece of metal the end of such a piece would not engage with but would pass back of the end of the tumbler.

The operating mechanism of this padlock 105 consists of but few parts and these are very simple and cheap, and yet the hasp can be securely locked closed and cannot be released without a key of the proper shape. Variations may be made by changing the 110 outline of the keyhole and also by changing the location of the wing on the end of the

guard which is engaged by the key and utilized to lift the barrier transversely from in front of the lower end of the locking tumbler.

The invention claimed is;

1. A padlock having a casing with a keyhole, a hasp with one end pivoted in the casing and its other end adapted to swing into and out of the casing, a spring tending to throw the hasp open, a pivoted tumbler having an end designed to engage the pivoted end of the hasp and hold it closed and having an end extending into the line with the keyhole, a spring tending to retain the tumbler in locking position, a spring guard having one end fixed and the other end yielding transversely with relation to the plane of movement of the tumbler, said yielding end having a barrier normally projecting against the side of the casing between the keyhole and the end of the tumbler, and a wedging wing projecting from said barrier and designed, when properly
- 10
- 15
- 20

engaged, to lift the barrier transversely out of the path from the keyhole to the lower end of the tumbler.

2. A padlock having a casing with a keyhole, a hasp with one end pivoted in the casing and its other end adapted to swing into and out of the casing, a spring tending to throw the hasp open, a pivoted tumbler having an end designed to engage the hasp and hold it closed and having an end extending into line with the keyhole, a spring tending to retain the tumbler in locking position, a spring guard having a barrier normally projecting between the keyhole and the end of the tumbler, a wedging wing projecting from said barrier and designed, when properly engaged, to lift the guard transversely out of the path from the keyhole to the lower end of the tumbler, and a shield extending from the wall of the casing adjacent to the edge of the keyhole to the guard.

LOUIS SNYDER.
